STABILIZED TRUCK

Edwin W. Webb, Chicago, Ill., assignor to Standard Car Truck Company, Chicago, Ill., a corporation of New Jersey

Application July 22, 1940, Serial No. 346,879

5 Claims. (Cl. 105—193)

This invention relates to car trucks.

It is one of the main objects of the present invention to provide novel and improved stabilizing devices for car trucks, the side frames of which are equipped with bolster columns of arcuate curvature in horizontal cross section, the said stabilizing devices acting to break down and prevent natural harmonic action of the bolster springs.

A further object is to provide novel and improved means for attaching wear plates to the bolster columns of side frames.

The objects and advantages of the invention will more fully appear from the following description, made in connection with the accompanying drawing, wherein like reference characters refer to the same or similar parts throughout the various views and in which,

Fig. 1 is a view in side elevation of a portion of a car truck embodying the invention, certain of the parts being broken away and shown in section to more fully illustrate the construction of other parts;

Fig. 2 is a horizontal section taken on the line 2—2 of Fig. 1 as indicated by the arrows;

Fig. 3 is a view looking toward the face of one of the wear plates employed;

Fig. 4 is a view in side elevation illustrating one of the bolts used for attachment of the wear plates; and

Fig. 5 is a vertical section taken on the line 5—5 of Fig. 4, as indicated by the arrows.

Referring to the drawing, portions of a side frame A of a car truck are illustrated. The side frame A is equipped with a bolster opening 6 defined by bolster columns 7 having wear plate receiving channels 8 therein. The inner faces 9 of the column channels are of concave arcuate curvature in horizontal cross section, as best shown in Fig. 2. Fitting within the channels 8 of the columns 7 are wear plates 10, these wear plates being of arcuate curvature in cross section and the convex faces of the wear plates being disposed against the column faces 9 and the concave surfaces of the wear plates being disposed inwardly.

The wear plates have bolt receiving openings 11 therein of peculiar construction. In forming these openings 11 parallelogram-shaped apertures are first punched in the plates 10, these apertures being of greater length than width. The apertures so punched are then countersunk from the inner faces of the wear plates 10, the diameter of the countersunk portions at the inner faces of the plates equaling the major axis

of the punched apertures, as best shown in Fig. 3. To secure the wear plates 10 in place on the columns 7, bolts 12 having heads of peculiar construction are employed. The heads of these bolts 12 form a pair of diametrically opposed lugs 12a which are of such size as to fit within the apertures 11 of the wear plates to prevent turning movement of the bolts relative to the wear plates. Between the two lugs 12a each bolt head is beveled at its edges to be snugly received within the countersunk portion of an aperture 11. With this arrangement when the bolts 12 are applied in position, the outer surfaces of the heads lie flush with the inner surfaces of the wear plates 10 and at the same time turning movement of the bolts is impossible. Of course, the bolts 12 project through properly formed openings in the columns 7 and take the usual washers 13 and nuts 14 which cooperate with the bolts to hold the wear plates in place. With this construction it becomes unnecessary to rivet the wear plates in place on the columns and the wear plates can be very easily applied, removed and replaced.

One end portion of a truck bolster B is received within the upper part of the bolster opening 6 of the side frame, the lower part of the bolster opening being widened relative to the upper part thereof to permit insertion of the bolster properly in place. The end portion of the bolster B is supported by the usual bolster springs 15 which rest on a lower spring cap 16 carried by the widened portion of the side frame A at the bottom of the bolster opening. These springs 15 are spaced transversely of the truck somewhat farther than usual for a purpose presently to appear.

The side surfaces of the end portion of the bolster B opposite the wear plates 10 are equipped with pockets 17 to receive wedges 18. The pockets 17 are of substantially triangular shape, as viewed in the vertical plane, taken transversely of the bolster with the hypotenuse of the triangle disposed inwardly. Accordingly, the bolster forms inclined surfaces 19 opposite the wear plates 10.

The wedges 18 which may be referred to as stabilizing members or stabilizing wedges are also of substantially triangular shape in side elevation, as viewed in Fig. 1, and these wedges have arcuately curved convex outer faces 20 which work against the inner concave surfaces of the wear plates 8. Of course, the surfaces 20 are of arcuate curvature in transverse cross section. The inner surfaces of the stabilizing wedges 18

have slight crowns 21 thereon for engagement with the inclined surfaces 19 of the bolster B. Crowns are given to these inner surfaces of the wedges so as to always permit of proper contact of the wedges with both the wear plates 20 and the inclined surfaces 19 of the bolster irrespective of slight mal-adjustment of the parts or turning movement of the bolster relative to the side frame.

In order that the stabilizing wedges 18 may be tied to the bolster B for ease in assembly, shipment, etc., cross pins 22 extending across the pockets 17 are provided, these cross pins being mounted in the opposite walls of the pockets. These pins 22 extend through enlarged cross openings 23 in the wedges 18, the openings being preferably of triangular shape in side elevation as shown in Fig. 1. These openings 23 permit of limited movement of the bolster B upwardly and downwardly relative to the wedges 18.

Extending between the bottoms of the wedges 18 and the spring caps 16 are stabilizing springs 24 which support the stabilizing wedges from the side frames. The bottoms of the wedges 18 are preferably configured to form spring centers for the springs 24.

The side surfaces of the end portion of the bolster B are preferably equipped with vertical ribs 25 having slanting abutment surfaces cooperating with slanting surfaces 26 formed at the inner and outer edges of the columns 7 to prevent anything more than but very limited lateral movement of the bolster relative to the side frames.

Of course, the structure illustrated will be duplicated at the other side of the truck. During travel of the truck equipped with the present invention, the natural harmonic action of the bolster springs 15 is prevented by reason of the use of the stabilizing wedges 18 and the stabilizing springs 24. At certain speeds of a car truck as the truck passes over rail joints, the actuation of the bolster springs is such that unless checked, the alternate compression and expansion of the springs is aggregative so as to produce severe bouncing action of the car and the goods carried therein. The stabilizing wedges backed by the stabilizing springs 24 and engaging the inner surfaces of the wear plates 10 and the inclined surfaces 19 of the bolster produce a damping action on the bolster springs 15 to prevent cumulative harmonic action thereof. By reason of the curved surfaces 20 of the wedges the stabilizing devices of the invention accommodate themselves to car trucks having bolster columns of arcuate curvature in transverse cross section and, as a result, if during movement of the truck one end of the bolster B moves ahead of the other end thereof, proper bearing is still secured between the bolster and the bolster columns and at the same time the stabilizing function is secured.

It will, of course, be appreciated that the mechanical equivalent of the present construction could be secured if the inner surfaces 9 of the bolster columns were made of convex rather than concave curvature and the wear plates 10 were oppositely curved and the surfaces 20 of the wedges were of concave curvature.

It will, of course, be understood that various changes may be made in the form, details, arrangement and proportions of the various parts without departing from the scope of the present invention, which, generally stated, consists in the matter shown and described and set forth in the appended claims.

The present application is similar to United States application for patent, Serial No. 161,244, filed August 27, 1937, allowed August 3, 1938, and forfeited, filed in my name and entitled "Stabilized truck."

What is claimed is:

1. In a car truck, a side frame having bolster columns of arcuate horizontal cross section defining a bolster opening, said columns being cylindrically disposed about a common vertical axis, a bolster received between said bolster columns, and stabilizing wedges interposed between said bolster and said columns, said wedges having surfaces of arcuate shape in horizontal cross section cooperating with the arcuate surfaces of said columns, and said wedges having freedom for limited lateral motion relative to said columns, bolster springs supporting said bolster from said side frame and stabilizing springs supporting said stabilizing wedges from said side frame.

2. In a car truck, a side frame having bolster columns of arcuate horizontal cross section defining a bolster opening, said columns being cylindrically disposed about a common vertical axis, a bolster received between said bolster columns, said bolster having diagonally inclined surfaces opposite said columns, stabilizing wedges interposed between the diagonally inclined surfaces of said bolster and said columns, said wedges having inclined surfaces cooperating with the inclined surfaces of said bolster and having other surfaces of arcuate shape in horizontal cross section cooperating with the arcuate surfaces of said columns, and said wedges having freedom for limited lateral motion relative to said columns, bolster springs supporting said bolster from said side frame and stabilizing springs supporting said wedges from said side frame.

3. In a car truck, a side frame having bolster columns of arcuate horizontal cross section defining a bolster opening, said columns being cylindrically disposed about a common vertical axis, a bolster received between said bolster columns, said bolster having diagonally inclined surfaces opposite said columns, stabilizing wedges interposed between the diagonally inclined surfaces of said bolster and said columns, said wedges having inclined surfaces cooperating with the inclined surfaces of said bolster and having other surfaces of arcuate shape in horizontal cross section cooperating with the arcuate surfaces of said columns, and said wedges having freedom for limited lateral motion relative to said columns, bolster springs supporting said bolster from said side frames, stabilizing springs supporting said wedges from said side frame, said bolster having wedge retaining walls inwardly and outwardly of said wedges longitudinally of the bolster, cross pins carried by said bolster and extending between said inner and outer walls thereof, said wedges having enlarged openings extending transversely therethrough and through which said pins extend, the said openings permitting upward and downward movement of said wedges relative to the bolster.

4. In a car truck, a side frame having a bolster opening therein and columns defining the bolster opening and of arcuate curvature in horizontal cross section, said columns being cylindrically disposed about a common vertical axis, a bolster working within said opening and having pockets of triangular shape in vertical transverse cross section in its sides opposite said columns, stabilizing members of wedge shape received within said pockets and having end surfaces of arcuate horizontal cross section cooperating with the arcuat:

surfaces of said columns, said wedges having freedom for limited lateral motion relative to said columns, bolster springs supporting said bolster from said side frame and stabilizing springs supporting said stabilizing members from said side frame.

5. In a car truck, a slide frame having bolster columns defining a bolster opening, a bolster received between said bolster columns, said bolster having diagonally inclined surfaces opposite said columns, stabilizing wedges interposed between the diagonally inclined surfaces of said bolster and said columns, said wedges having inclined surfaces cooperating with the inclined surfaces

10 of said bolster and having other surfaces cooperating with said columns, bolster springs supporting said bolster from said side frame, stabilizing springs supporting said wedges from said side frame, said bolster having wedge retaining walls inwardly and outwardly of said wedges longitudinally of the bolster, cross pins carried by said bolster and extending between said inner and outer walls thereof, said wedges having enlarged openings extending transversely therethrough and through which said pins extend, the said openings permitting upward and downward movement of said wedges relative to the bolster.
